WINDING MECHANISM

Francis C. Evans, Dongan Hills, N. Y., assignor to
 American District Telegraph Company, Jersey
 City, N. J., a corporation of New Jersey

Original application December 16, 1941, Serial No.
 423,130. Divided and this application August
 4, 1942, Serial No. 453,509

8 Claims. (Cl. 185—43)

This invention relates to winding mechanism for alarm signal transmitters and the like, the present application being a division of my prior application, Serial No. 423,130, filed December 16, 1941.

In general terms the object of the present invention is to improve the winding mechanism of spring motor driven devices such as alarm transmitters.

Another object of the invention is to provide a winding mechanism for an alarm signal transmitter which insures that the winding of the transmitter or other delicate apparatus will only be done properly and without damage even when the winding is done by a careless or unskilled attendant.

Other objects are to confine all operations of the spring winding and driving mechanisms within safe limits; to insure constant speed of operation for each time the spring mechanism is wound, and to insure constant torque within certain limits by always operating the spring mechanism within predetermined limits.

An additional object is to provide a winding mechanism which will always be wound to the desired extent by the key or winding member and which cannot be only partially wound or overwound.

A still further object is to provide winding mechanism for an alarm signal transmitter or the like which is of such character that the normal operation of the alarm signal transmitter cannot be interfered with or the transmitter deranged by manipulation of the winding key in the hands of a person who is seeking to disable or block the operation of the transmitter.

Other objects and advantages of the invention will appear from the following description of the embodiment thereof shown in the accompanying drawings, wherein:

Fig. 1 is a perspective view of a portion of the transmitter with the supporting structure omitted.

Figs. 1A, 1B and 1C are fragmentary views of a portion of the key winding mechanism shown in Fig. 1;

Fig. 2 is a front plan view of the signal transmitter shown in Fig. 1 with the cover removed; and

Figs. 3 to 8, inclusive, are detail views of the spring motor trip mechanism at successive stages of the winding operation, at the completion of which the transmitter is operative to send a restoration signal and the spring motor is tensioned for the transmission of an alarm signal during a subsequent period.

The embodiment of the invention illustrated is a fire alarm transmitter arranged for sending coded alarm signals to a central station, the trans-

mitter being adapted to be released either manually or automatically by temperature responsive devices, as described in detail in the parent application referred to above. However, the winding mechanism for the spring motor as disclosed and claimed herein is adapted for use in many other types of mechanism including horological apparatus.

Referring to Figs. 1 and 2, the alarm transmitter comprises a code impulse wheel 10 mounted on a shaft 11 which is driven through a gear 12 and pinion 13 from a main shaft 14 to which the spring driving motor is connected. The motor preferably comprises two coiled springs 15 and 16 arranged in parallel so that, if either spring breaks, the impulse wheel 10 is driven by the other spring, although if desired a single spring driving structure obviously may be employed. The impulse wheel 10 is provided with a series of teeth 18 adapted to engage the contact spring 19 when the impulse wheel is rotated and thereby open the contacts 20 to break the transmission circuit and send code impulses thereover in a manner well-known in the art.

The tripping of the impulse wheel 10 permits said wheel to be driven by the spring motor, and in the prior application referred to above means for either automatically or manually tripping the transmitter is described and claimed. As shown, the spring motor is connected through the gears 12, 22, 24 and 26 and the intermediate pinions 13, 23, 25 and 27 to the governor fan 28, the latter also serving as a latch member for normally restraining the rotation of the impulse wheel 10. The gearing referred to is provided for the purpose of rotating the governor fan 28 at the desired speed. The rotation of the governor fan 28 is normally prevented by a movable latch member 31 which may be moved either in a horizontal or a vertical plane to disengage the hook 32 of said latch from the edge of the governor fan 28. As shown, notches 33 and 34 are provided in the opposite edges of the fan 28 to permit the latch to be disengaged therefrom by a horizontal movement, the notch 34 being wider than the notch 33 so that, when the edge of the narrow slot is cleared, the governor fan 28 will rotate freely.

The manual trip mechanism includes an operating arm 36 secured to a movable rod 37 pivoted at the point 38, said rod being attached to a lateral bar 39 which is slotted at the outer end thereof to receive the latch 31. Thus, it will be seen that movement of the operating arm 36 in a horizontal direction serves to deflect the latch 31 to a position in which the governor fan 28 will revolve freely and permit the spring motor 15, 16 to rotate the code impulse wheel 10. It will be further noted that the employment of the governor

fan 28 as a latching element serves to reduce the frictional engagement between the elements 28 and 32 of the latch, since said fan is geared up with respect to the motor shaft 14 and impulse wheel shaft 11, thereby reducing the torque on the fan shaft.

The winding mechanism for the spring motor as claimed herein obviously may be incorporated in various types of spring motor mechanism, as pointed out above. A key 40 is provided for turning the shaft 14 to wind the spring motor. In the embodiment shown the gear 12 is journaled freely on the shaft 14, whereas the ratchet wheel 41 is secured to said shaft. A pawl 42, which is pinned to the gear 12, is adapted to engage the ratchet wheel 41 to couple the motor shaft to said gear when the transmitter is tripped and to permit the motor shaft 14 and wheel 41 to turn in a clockwise direction during the winding operation without turning the gear 12. The gear 12 is held positively against movement during the winding operation by means of a pin 45 secured thereto and adapted to abut against a lug 46 on a rotatable stop member 47 which is pinned to the frame of the transmitter. The stop member 47 is also provided with a projecting arm 48 extending into the path of movement of a pin 49 carried by a wheel 50 journaled on the shaft 14. The wheel 50 in turn is driven through a lost-motion connection from a cam 51 having a lateral pin 52 extending into an arcuate slot 53 in the wheel 50. The cam 51 and slotted hub 55, which is adapted to receive the key 40, are secured to the motor shaft 14 so that the stop member 47 is turned by the engagement of the pin 49 with the arm 48 when the spring motor is wound up. The stop member 47 is held in either the stop or release position by a spring 60 having a notch engaging the cam projection 61 on said stop member.

It will be noted that the cam member 51 is provided with a peripheral slot 63 and a radial-notch 64, the former being provided for a circuit controlling function and the latter to control the movement of the bar 37 through the pin 65 for the purpose of releasing the transmitter to send a restoration signal when the spring motor is fully wound (or the transmitter "restored" to its normal operative condition). The notch 64 is provided with one sloping edge and one steep or perpendicular edge whereby the cam 51 will throw the latch member or lever 31 suddenly into tripping position as the cam turns in a counterclockwise direction when the transmitter is operating to send the restoration signal. During the winding of the spring motor, a projecting arm 66 on the stop member 47 holds the pin 65 on the trip arm 37 out of engagement with the notch 64 on the cam 51 so that the winding operation is not interfered with by the engagement between the said pin and notch. Since the transmission of the restoration signal is not a feature of the invention to be claimed herein, a further detailed description of this function is deemed unnecessary. However, the angular movement of the winding shaft after the motor is wound and the key removed prevents the blocking or interference with the transmitter by the key or another element engaging the hub 55, since the slot therein moves behind the cover or shield 68.

The key entrapment and camming mechanism includes a stationary covering shield or yoke 68 having a keyhole through which the key 40 may be inserted with the pin 70 thereon extending laterally, as shown in Figs. 1 and 2. When the key 40 is inserted into the hub 55 in this manner

to wind the spring motor, the pin 70 engages the slot in the hub 55 on the motor shaft 14 so that, when the key is turned in a clockwise direction, the shaft 14 turns with the key and tensions the motor springs 15 and 16. The winding mechanism is shown in the unwound condition in Fig. 1.

When the key has been turned approximately 120°, the pawl 42 engages a notch in the ratchet wheel 41 on the shaft 14 and prevents the return of the shaft so that the key 40 is trapped underneath the left hand edge of the keyhole in the yoke 68. After the key is turned another 120°, the pawl 42 engages a second notch in the ratchet wheel 41, the spring motor becoming more tightly wound but not completely wound until the shaft 14 has made a complete turn. In the meantime the turning of the cam 51 turns the cam 50 through the connection including the pin 52 so that the pin 49 is no longer holding the stop member 47 in the transmitter-stopping position, but the member 47 cannot move from such position, since the spring 60 and lug 46 retain it in the stop position. As the rotation of the key is continued through another 120°, the notch 64 in the cam 51 will pass under the pin 65, which is prevented from falling into the said notch by the engagement of the projecting arm 66 on the stop lever 47 with the tripping arm 37.

The key entrapment mechanism further includes a pivoted lever 71 which is pinned to the upper edge of the shield or yoke 68 by the pin 72, as shown more clearly in Figs. 1A, 1B and 2. The curved lever 71 extends around approximately one-half of the periphery of the hub 55 and is normally biased toward the position shown in Fig. 1A by a leaf spring 74. The lower or outer end of the curved lever 71 is tapered or wedge-shaped, as shown at 75 in Fig. 1C. Thus, it will be apparent that, since the pin 70 is sufficiently long to project beyond the circumference of the hub 55, after the key 40 has been turned about 300°, it will be trapped behind the lever 71 so that it cannot be withdrawn until the pin 70 in the key is turned beyond the end of the lever 71, and the spring motor will be completely wound up. It will be noted that the lever 71 extends past the bottom of the keyhole in the yoke 68 so that the key actually has to be turned about 30° more than a complete turn before the pin 70 passes beyond the end of the lever. Since the pawl 42 engages a notch in the ratchet wheel 41 when the key has completed a full turn, the additional twist of the key will further tension the spring motor so that, when the key is released, the spring motor will return the same to the position in which shaft 14 has just made one complete turn. During this slight angular return movement of the key, the pin 70 rides up on the cam surface 75 of the lever 71 so that the key is ejected from the hub 55 on the winding shaft.

Since the complete rotation of the cams 50 and 51 has effected the oscillation of the stop member 47 to its alternate or release position, as shown more clearly in Figs. 6 and 7, the gear 12 of the transmitter is released and is operated by the spring motor, after the key 40 is withdrawn, for a limited movement sufficient to rotate the code impulse wheel 10 to send the restoration signal. The transmitter is then stopped by the dropping of the pin 65 into the notch 64 in the cam 51 until the transmitter is tripped to send an alarm signal consisting of a plurality of revolutions of the code impulse wheel. The tripping of the transmitter when the alarm signal is to be sent permits the spring motor to rotate the gear 12

until the pin 45 again engages the lug 46 on the stop member 47. Inasmuch as the initial rotation of the motor shaft 14 in sending the restoration signal turned the slot in the hub 55 on the winding mechanism underneath the cover plate or yoke 68, it is impossible to stop or derange the operation of the spring motor to rotate the drive shaft 14 by inserting the key 40 or other similar tool through the keyhole. The key 40 cannot be reinserted into engaging relation with the winding hub 55 until the transmitter has run down and the spring motor has to be rewound.

Referring to Figs. 3 to 8, inclusive, Fig. 3 illustrates the spring motor trip mechanism together with a ratchet wheel and motor shaft in the run-down condition. Fig. 4 illustrates the trip mechanism after the key has been turned 120° in the winding operation. Fig. 5 illustrates the same elements after the key has been turned 240°, and Fig. 6 through 360° of rotation. Fig. 7 illustrates the relation of the ratchet wheel 41 and the pawl 42 when the key is turned beyond the fully wound position in order to enable the key to be withdrawn, as described above. Fig. 8 illustrates the degree of rotation of the motor shaft and gear 12 at the end of the restoration signal when the code wheel is stopped by the movement of the lever 37 when the pin 65 drops into the notch in the cam 51.

Various modifications of the foregoing mechanism will readily suggest themselves to those skilled in the art without the exercise of inventive skill and without departing from the spirit and scope of the invention as defined by the appended claims.

I claim:

1. In combination, a spring driven signal transmitting device comprising a winding mechanism and a key, said key including a member projecting therefrom for engaging said winding mechanism, a shielding device associated with said winding mechanism and provided with an opening for admitting said projecting member on said key, said shielding device comprising a key-trapping portion behind which said projecting member of the key must be turned during the winding operation to entrap the key when the winding operation is started, a key retaining member pivoted on said shielding device and engaging said projecting member of the key in that portion of the rotational angle of said key for continuing the entrapment of the key until a predetermined degree of rotation is accomplished and a spring biasing said pivoted member to force it into a releasing position after said predetermined degree of rotation of the key is effected to permit said key to be extracted from the device.

2. In combination, a spring driven signal transmitting device comprising a winding mechanism and a key, said key including a member projecting therefrom for engaging said winding mechanism, a shielding device associated with said winding mechanism and provided with an opening for admitting said projecting member on said key and comprising a key-trapping portion behind which said key projection must be turned during the winding operation to entrap the key after said operation has started, a key retaining member in said shielding device engaging the outer side of the projecting member of said key in that portion of the rotational angle of said key for continuing the entrapment of the key

until a predetermined degree of rotation is accomplished, said projecting member on the key clearing said retaining member after a predetermined degree of rotation of the key whereby said key may be extracted from the mechanism after such rotation.

3. In combination, a spring driven signal transmitting device comprising a winding mechanism and a key, a shielding device associated with said winding mechanism and provided with an opening for admitting said key, said device including a key-trapping portion behind which said key must be turned during the winding operation to entrap said key after said operation has started,

10 15 a key retaining member in said shielding device engaging said key for a portion of the rotational movement of the key to continue the key entrapment function until 360° of rotation is completed and a spring for biasing said retaining member into a normal position behind the key after complete rotation of said key whereby the key is cammed from engagement with the winding mechanism.

4. In combination, a spring driven device comprising a winding mechanism and a key for engaging said winding mechanism, a shielding device associated with said winding mechanism and provided with an opening for admitting said key, said device comprising a key-trapping portion or element behind which said key must be turned during the winding operation to entrap said key after said operation has started and a key retaining member at said opening in the shielding device engaging said key for continuing the entrapment of the key for a predetermined degree of rotation of the key.

5. In combination, a spring driven device comprising a winding mechanism and a key for engaging said winding mechanism, a shielding device associated with said winding mechanism provided with an opening for admitting said key and key ejecting means including a member engaging said key after a predetermined degree of rotation thereof during the winding operation.

45 6. In combination, a spring driven device comprising a winding mechanism and a key for engaging said winding mechanism, means for entrapping the key during a predetermined rotation thereof and for releasing the key when the winding mechanism has completely wound the spring motor, and means for limiting insertion of said key into winding engagement with said winding mechanism to a predetermined position of said winding mechanism.

55 7. In combination, a spring driven device comprising a spring motor, a winding mechanism for said motor and a key for engaging said winding mechanism, means for ejecting the key from the winding mechanism when said motor is completely wound, and means for preventing reinsertion of the key until the motor requires rewinding.

60 65 8. In combination, a spring driven device comprising a spring motor, a winding mechanism and a key for engaging the winding mechanism, means for preventing the withdrawal of the key from the winding mechanism before the mechanism is fully wound and for preventing greater than a predetermined rotation of the key to prevent overwinding, and means for camming the key from the winding mechanism when the spring motor is fully wound.
